UNITED STATES PATENT OFFICE.

WARREN M. MANSFIELD, OF MOLINE, AND RAYMOND HENRY, OF ROCK ISLAND, ILLINOIS, ASSIGNORS TO MOLINE PLOW COMPANY INCORPORATED, OF MOLINE, ILLINOIS, A CORPORATION OF VIRGINIA.

FORGED GEAR.

Original application filed March 16, 1921, Serial No. 452,749. Divided and this application filed May 3, 1923. Serial No. 636,360.

To all whom it may concern:

Be it known that we, WARREN M. MANSFIELD and RAYMOND HENRY, citizens of the United States, residing at Moline, county of Rock Island, State of Illinois, and Rock Island, county of Rock Island, State of Illinois, respectively, have invented certain new and useful Improvements in Forged Gears, of which the following is a specification.

The invention relates to a forged gear. It relates particularly to large driving gears for use with tractors. The application is a division of our copending application, Serial Number 452,749, filed March 16, 1921.

The large driving gears on the drive wheels of tractors are subjected to very severe strains because they transmit all the driving torque in all the various positions of the tractor wheels. They are also subjected to hard wear owing to the fact that tractors usually operate through dust and dirt. The gears must be hard to withstand the wearing action but, on the other hand must not be so brittle, that they will not withstand the stresses and strains to which they are subjected. Gears of cast iron and cast steel have been employed but have not satisfactorily met the requirements. Such gears either break too easily or wear out too quickly. The present invention relates to a forged gear.

The chief object of the invention is to provide an improved forged gear.

A more specific object is to provide a forged gear made in sections which may be readily connected together.

Other objects and advantages of the invention will appear from the specification and drawings.

An embodiment of the invention is illustrated in the copending drawings, in which

Figure 1 illustrates a piece of metal stock out of which a section of the gear may be forged.

Figure 2 illustrates the shape of the gear section after the first operation.

Figure 3 shows the shape of the gear section after another operation.

Figure 4 is a side elevation of the gear section after another operation.

Figure 5 is a plan view of the gear section illustrated in Figure 4.

Figure 6 illustrates the assembled gear. 55

In order that the construction of the gear may be clearly understood, the process of making it will first be described.

The metal stock out of which the gear is made is preferably in the form of a round 60 bar 1, as illustrated in Figure 1. This bar is cut to the appropriate length and heated to a forging temperature.

The heated metal bar is then bent or shaped on the edge of a blocking die or 65 "edger" and placed in an impression in the blocking die. It is worked back and forth between this impression and the "edger" until the bar is forged to the shape and form illustrated in Figure 2. The exact 70 shape of the different portions of this piece may be varied to suit the requirements of the gear being made. The general principle followed is that the metal is thickened at certain places and thinned at others so that, 75 when it is placed in other blocking and finishing dies, there will be the proper amount of metal at the proper places to completely fill the impression in the die so that the finished gear section will be completely filled 80 out to the shape of the die. The section, as shaped in Figure 2, has a tong hole 2 at one end, by means of which the piece may be handled.

The crudely shaped gear section is then 85 reheated, if it has not retained sufficient heat to continue the forging process, and it is put in a finishing die where it is forged to the shape shown in Figure 3. The forging is continued until the die is filled and the die 90 faces strike one another, indicating that the piece is finished. The gear section, as forged, takes accurate shape with a peripheral portion 4, a spoke or radio portion 5, and a hub portion 6. Conical projections 95 7, 8, and 9, and tapered holes 11, 12, and 13 are formed during this operation.

During the finishing operation, the excess metal is forced out and forms a rough edge 10 called the "flash." The gear sec- 100

tion, as illustrated in Figure 3, is taken from the finishing dies to trimming dies where this "flash" 10 is trimmed off, leaving a completed forging gear section as illustrated in Figures 4 and 5.

This finished section forms one-sixth of a complete gear although it will be understood, that the exact number of sections can be varied as required.

10 It will be observed that the conical projections 7, 8, and 9 are complementary to the holes 11, 12, and 13 respectively. For example, referring to Figures 4, 5, and 6, if a section exactly like the one illustrated in 15 Figures 4 and 5 is fitted on to the one illustrated in Figure 6, the hole 11 of the second section would fit over the conical projection 7, and the holes 12 and 13 of the section illustrated in Figure 4 would fit over 20 conical projections 8 and 9 on the second section. The hub portion of the one section overlaps the hub portion of the other and likewise a part of the peripheral portion of one section overlaps a part of the peripheral portion of the other section.

25 The sections are riveted together by means of the conical projections and the tapered holes. By referring to Figures 4 and 5, it will be noted that the holes are tapered in 30 the opposite direction to the projections, so that when the projections are inserted in the holes, they may be riveted so as to firmly lock the parts together.

35 The gear is assembled by placing a forged gear section in an assembling press. When the next gear section is completed, it is placed in the assembling press with the conical projections of one section inserted over the complementary tapered holes in the 40 other section. The forging operations and the assembling of the forged gear sections in the assembling die are preferably carried out rapidly and simultaneously so that the gear may be assembled before the forged 45 sections become too cold. However, if they should become too cold in the assembling press, means is provided, in the nature of a gas jet or the like, for keeping the projections on the gear sections heated to a temperature that will permit them to be riveted.

50 After a sufficient number of gear sections have been placed in the assembling die to make a complete gear, the dies are closed and the ends of the conical projections are 55 riveted over to hold all the sections rigidly together.

When the gears are removed from the assembling press, they constitute a rigid forged gear in which the sections overlap 60 one another and are held rigidly together by interval projections on one section riveted to the other section.

65 The gear is then machined in the same manner as if it were an interval gear and teeth are cut in its periphery.

This process of making the gear makes it possible to use standard stock material; makes it possible to use relatively small forging hammers and dies, and it results in very little waste stock. If a large gear, 70 such as is used in most tractors, were to be forged as a unit, the size of the hammers and dies would be prohibitive and the cost of the large pieces of metal stock would be high. There would also be excessive 75 waste in the various parts that would have to be cut out of the large block of material.

It is possible to obtain on the market, in the form of bars, a variety of the best gear steels. It is therefore possible to make the 80 gear herein described at a relatively small expense from a range of materials carried in stock at small expense. If it were necessary to carry in stock large blocks of metal, such as would be necessary if the gear were 85 to be forged as a unit, it would not only be very difficult to get a wide range of materials, but it would be also very costly and, in fact, too expensive to be practical.

The process is relatively simple and inexpensive since only a few simple forging operations are required. The gear sections are duplicates of one another. This simplifies the assembling operation since the operators do not have to use special care to 95 see that special parts are fitted at the right place.

99 The gear is both strong and durable. It is strong because each section is a strong forged section and these sections are interlocked with one another by being overlapped. They are tightly riveted together by rivets of liberal size, interval with the forged sections. The gear is durable because it is made of selected gear material and that material is subjected to a forging operation which increases its durability.

100 It is to be understood that the gear shown is for purposes of illustration and that variations may be made in its construction without departing from the spirit and scope of the invention as defined by the appended 110 claims.

We claim:

115 1. A forged gear having more than two spokes, comprising a plurality of forged gear sections each comprising a spoke portion having a hub portion on one end and a rim portion on the other end, the hub and rim portions of one section partially overlapping those of the other, and means fastening the sections together.

120 2. A forged gear comprising a plurality of forged gear sections each comprising a spoke portion having a hub portion extending in one direction from one end thereof and a peripheral portion extending in the other direction from the other end thereof, said sections having overlapping portions, and means connecting the sections together.

3. A forged metal gear having more than two spokes, comprising a plurality of gear sections each having a spoke portion with a hub portion on one end and a gear-tooth section on the other, said sections being united together by means of projections on one section extending through openings in the other and being riveted to hold the sections together. 20
- 5 4. A forged metal gear having more than two spokes, comprising a plurality of gear sections each of which comprises a spoke portion having a hub portion projecting in one direction from one end thereof and a gear- 25
10 tooth section projecting in the other direction from the other end thereof, the hub and gear-tooth portions of one section partially overlapping the hub and gear-tooth portions of the adjacent section, and means fastening the sections together. 30
- 15

5. A forged gear section comprising a spoke having an arc-like hub portion projecting from one end thereof and an arc-like gear-tooth section projecting from the other end thereof, said hub and gear-tooth sections having portions adapted to fit similar portions on adjacent sections so that a plurality of said sections may be assembled to form a complete gear having more than two spokes. 30

In testimony whereof, we affix our signatures.

WARREN M. MANSFIELD.
RAYMOND HENRY.
